UNITED STATES PATENT OFFICE.

EDUARD LEISSNER, OF NEW YORK, N. Y.

DESIGN FOR WALL-PAPER.

SPECIFICATION forming part of Design No. 13,150, dated August 8, 1882.
Application filed June 30, 1882. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

A represents a vine bearing upon it circular leaves *a*, set thickly upon stems growing from

the vine. This vine *A* also bears bunches *f* of flowers, some widely open, some partly open, and some in bud, and also bunches *h*, *c*, and *b* of the same kind of flowers as the bunch *f*. The repetition of this vine *A*, with its leaves and bunches of flowers, forms the design.

I claim—

The design for wall-paper, consisting of the vine *A*, containing figures *a*, *b*, *c*, *f*, and *h*, substantially as shown.

EDUARD LEISSNER.
